US0D1106468S

(12) **United States Design Patent** (10) Patent No.: **US D1,106,468 S**
(45) Date of Patent: ** Dec. 16, 2025

(54) **GARMENT FOR RESPIRATORY THERAPY**

(71) Applicant: **HILL-ROM SERVICES PTE. LTD.**,
Singapore (SG)

(72) Inventors: **Qingqing Koh**, Singapore (SG); **Wei Bian**, Singapore (SG); **Moei Ting M. Kuwn**, Singapore (SG); **Kok Boon R. Ong**, Singapore (SG); **Tay Kean Peng**, Singapore (SG); **Gee Han Png**, Singapore (SG); **Aaron A. Ayu**, Singapore (SG); **Yaolong Lou**, Singapore (SG); **Susan E. Malaret**, Singapore (SG); **Susan E. Malaret**, Chanhassen, MN (US)

(73) Assignee: **HILL-ROM SERVICES PTE. LTD.**,
Singapore (SG)

(**) Term: **15 Years**

(21) Appl. No.: **29/997,689**

(22) Filed: **Apr. 9, 2025**

Related U.S. Application Data

(62) Division of application No. 29/805,540, filed on Aug. 27, 2021, now Pat. No. Des. 1,078,063.

(51) **LOC (15) Cl.** **24-04**

CLAIM

The ornamental design for a garment for respiratory therapy, as shown and described.

DESCRIPTION

FIG. 1 is a perspective view of a garment for respiratory therapy in accordance with our design;
FIG. 2 is a front elevation view of the garment for respiratory therapy of FIG. 1;
FIG. 3 is a rear elevation view of the garment for respiratory therapy of FIG. 1;
FIG. 4 is a first side elevation view of the garment for respiratory therapy of FIG. 1;
FIG. 5 is a second side elevation view of the garment for respiratory therapy of FIG. 1;
FIG. 6 is a top plan view of the garment for respiratory therapy of FIG. 1;
FIG. 7 is a bottom plan view of the garment for respiratory therapy of FIG. 1;
FIG. 8 is a front elevation view of the garment for respiratory therapy of FIG. 1, similar to FIG. 2, but with a flap of the garment folded back;

FIG. 9 is a perspective view of an inflatable bladder of the garment for respiratory therapy of FIG. 1;
FIG. 10 is a front elevation view of the inflatable bladder of FIG. 9;
FIG. 11 is a rear elevation view of the inflatable bladder of FIG. 9;
FIG. 12 is a first side elevation view of the inflatable bladder of FIG. 9;
FIG. 13 is a second side elevation view of the inflatable bladder of FIG. 9;
FIG. 14 is a top plan view of the inflatable bladder of FIG. 9; and,
FIG. 15 is a bottom plan view of the inflatable bladder of FIG. 9.
The broken lines in FIGS. 1-15 are directed to portions that form no part of the claimed design.
